UNITED STATES PATENT OFFICE

FRANK M. BACON, OF NORTH ADAMS, MASSACHUSETTS

MACHINE FOR WINDING CLOTH, ETC., ON CLOTH BOARDS

Application filed March 28, 1931. Serial No. 526,073.

This invention relates to improvements in cloth winding machines, for use in textile mills and factories, for winding fabrics in bolts upon boards, and the principal objects of the invention are, to provide a machine having a pair of spaced cross-heads adapted to be rotated together one of the cross-heads carrying a pivoted board holder, the outer end of the holder being adapted to be locked in the opposite cross-head when the cloth board is positioned on the holder; to provide novel means for locking the outer ends of the holder in the cross-head; also to provide means for locking the cross-heads against rotation when the holder is swung out of alignment with the cross-heads, also to provide novel means for positioning the cloth board on the holder; also to provide a novel cloth board which will be inexpensive, light in weight, and of a form enabling it to be easily positioned in or detached from a winding machine, said board having tubular side members through which the rods on the holder are passed for supporting the board in such machine so that fabric or other material can be uniformly wound upon the board, and the wound body of fabric and board easily removed from the machine; also to provide a novel label attaching strip for the cloth board.

I will explain the invention with reference to the accompanying drawings which illustrate one practical embodiment thereof to enable others to adopt and use the same; and will summarize in the claims the novel features of construction and novel combinations of parts for which protection is desired.

In the drawings:

Fig. 1 is a side elevation of a cloth winding machine including an embodiment of my invention.

Fig. 2 is a horizontal section on the line 2—2, Fig. 1.

Fig. 3 is a plan view, on an enlarged scale, of the holder and winding board detached.

Fig. 4 is an enlarged section on the line 4—4, Fig. 3.

Fig. 5 is an enlarged section on the line 5—5, Fig. 3.

Fig. 6 is an enlarged plan view of a portion of the cloth board, partly in section.

Fig. 7 is a section on the line 7—7, Fig. 6.

Fig. 8 is a perspective view of a label attaching means for the cloth board.

Fig. 9 is an enlarged perspective view of the means for locking the holder against rotation when swung out of alignment with the cross-heads.

Referring to the drawings, in the several views of which like parts are designated by the same reference characters, the machine in which the improvements are shown comprises two end frames 1, in which are provided bearings for a main power shaft 2, shown as having mounted thereon power means, such as fast and loose pulleys 3, 4, respectively. The end frames are connected by a top piece 5, and in suitable bearings supported thereby are mounted the two aligned and longitudinally spaced shafts 6, 7, constituting a part of my improved board holder and which are provided at their adjacent ends with suitable cross-heads 8, 9, respectively.

Preferably, the shafts 6, 7, are connected with the cross-heads by right and left hand threads, respectively, so that the parts may be detached, and the shafts replaced by others of different diameters or lengths and so that when the machine is operating the board holder will run perfectly true and there will be no danger of the cross-heads and shafts being accidentally disconnected.

Each of the shafts 6, 7, is shown as being geared to the main drive shaft 2, so as to be positively rotated at the same speed, and in the same direction.

As shown, the winding board supporting rods 10 and 11 of the holder are connected to a yoke 12, having arms which are spaced apart to receive the ends of cross-head 8, the yoke 12 being pivotally connected to said cross-head 8 by a pivot pin or bolt 12a, thus permitting rods 10 and 11 to swing bodily about an axis extending transverse of the shaft 6 whereby the outer ends of said rods 10 and 11 may be moved into and out of engagement with the opposite cross-head 9. Rods 10 and 11 constitute a support during the winding of the fabric upon the cloth board, hereinafter referred to, upon which

the fabric is wound as the shafts 6, 7, are rotated.

In the outer face of the other cross-head 9 of the holder are formed guide grooves extending in diametrically opposite directions, said grooves receiving the slides 15 and 16, and having at their outer ends lateral branches 14, forming notches opening through one edge of the cross-head. The outer end walls of the notches 14 are provided with parti-cylindrical recesses 14a forming bearings for the board supporting rods 10 and 11 of the holder; and slides 15, 16, are adapted to be moved in the grooves in the cross-head toward and from a position where they will engage said rods and hold them in fixed relation to the cross head 9. The outer ends of slides 15 and 16 are likewise provided with parti-cylindrical recesses 15a and 16a for engaging the rods 10, 11.

Any suitable means may be provided for adjusting the slides 15, 16. As shown, a lever 20 is pivoted on the cross-head 9 and connected by links 21, 22, with the slides. By swinging the lever 20 outward away from the cross-head, the blocks or slides 15, 16, will be drawn inwardly toward each other and out of engagement with the rods 10, 11, and thereafter said rods and the board and fabric supported thereby can be swung bodily about pivot bolt 12a into the position shown in dotted lines in Fig. 2, so that the cloth board can be withdrawn from the rods 10 and 11 and a new board positioned thereon.

I provide means for locking the shaft 6, and cloth board holder against accidental rotation when the latter is swung out of alignment with the shaft 7 or into position shown in dotted lines in Fig. 9 for removing or replacing a cloth board. As shown a locking plate 23 is fixedly secured, as by bolts, to the top piece 5 for the frame, and has a hole therein for the passage of shaft 6 therethrough, the plate 23 being disposed immediately adjacent the cross-head 8. A locking bolt 24 is pivoted at one end on the yoke 12 between lugs 12a, the other end passing through a bore in an offset lug 8a at the inner end of cross-head 8 adjacent the plate 23, said bolt 24 being adapted to be projected through an arcuate slot 23a when the yoke 12 is pivoted, but the end of bolt 24 being retracted out of engagement with the slot 23a when the rods 10, 11 of yoke 12 are engaged with the cross-head 9.

The improved winding board (Figs. 5-6-7) includes tubular side bars 30 connected by end bars 31, and a covering 32 which is commonly made of suitable paper passed about and secured to the frame formed by the bars 30, 31.

Preferably, the end members 31, as well as any intermediate transverse braces between the side members 30, are also of tubular form, and it is preferred to make all of said

tubular frame members of paper. The well known spirally wound paper tubes have been found particularly adapted for use in this connection, as they provide a very light, inexpensive, but strong frame.

The paper covering for the board is so applied that it does not in any manner obstruct the passages in the side members 30 of the board frame, and these are of a diameter which permits the board to be easily slipped over or withdrawn from the rods 10, 11.

In order that boards of various lengths may be used, it is preferred to provide the board holding means with an adjustable abutment 40. This, as shown, comprises a plate or bar extending transversely across the space between the rods 10, 11, with which its ends may engage, if desired, and ears or lugs projecting laterally therefrom are adjustably connected to similar ears or lugs on the yoke 12. By means of fastening nuts 41, the abutment 40 may be secured in various positions lengthwise of the rods 10, 11. At the opposite end the winding board will abut the face of the cross-head 9.

When the desired quantity of fabric has been wound upon the board, and the board is removed from the machine, a label carrying plate 50 (Fig. 8) may be applied thereto, as shown in Figs. 6 and 7. This plate is provided on one face at both ends with projections 51, which are of a diameter to fit closely within the tubular side members 30 of the board frame. Plate 50 may be of any suitable material, such as paper, or felt, to which an adhesive can be applied when the plate is positioned at the end of the board, so that it will be securely retained in position. By this means the finished bolt is given a neat and attractive appearance, the openings in the ends of frame members 30 being closed.

The board holder, comprising the rods 10, 11, the associated cross-heads and shafts 6, 7, may be applied as a unitary structure to any existing winding machine or be incorporated in newly constructed machines; also the shafts 6, 7, may be of any suitable diameter to fit the proper gears of existing machines, said shafts being readily applied to the cross-heads 8, 9.

In the drawings many of the parts are shown more or less diagrammatically, and there can be modification of some of the details shown without departing from the invention, which is not intended to be limited to the exact arrangement shown, except as described in the appended claims.

I claim:

1. In a winding machine, aligned rotatable cross-heads, a yoke pivoted on one cross-head, a board holder carried by the yoke and adapted to be normally engaged with the opposite cross-head; and means on the yoke for automatically locking the cross-heads

against rotation when the holder is swung out of alignment with the cross-heads.

2. In a winding machine as set forth in claim 1, said means comprising a locking bolt pivotally mounted on the yoke and extending through a guide on the related cross-head, and a fixed plate disposed opposite the end of the bolt and having a slot adapted to receive the bolt when projected by pivoting 10 the yoke.

3. In combination, two aligned shafts sections, cross-heads carried by said sections; a board holder pivotally mounted on one of the cross-heads and adapted to swing about 15 an axis extending transversely of the axis of the sections, said holder having spaced projections at the outer corners thereof; the other cross-head having notches formed therein opening through one edge and adapted to receive the projections on the holder; and manually adjustable means movable radially of 20 the notches for locking said projections therein.

4. In a combination as set forth in claim 25 3, said means comprising a pair of movable slides mounted between the notches on the last said cross-head adapted to engage said projections when positioned in said notches; and a manually actuatable member for simultaneously moving said slides in opposite 30 directions to and from engagement with said projections.

5. In a fabric winding machine, the combination of two aligned shafts sections; 35 cross-heads secured to the said sections; two parallel rods connected at one end to one of the cross-heads and mounted to swing about an axis extending transversely of the axis of the head; a winding board having tubular 40 side members through which the rods may be passed whereby the board may be positioned on or withdrawn from the rods, and means for locking the outer ends of the rods to the other cross-head.

45 6. In a board holder for fabric winding machines, the combination of two aligned driving shafts, cross-heads secured to the said shafts, one of said cross-heads having formed in its face opposing the other cross-head diametrically opposite grooves each having a laterally projecting branch opening through an edge of the cross-head, a pair of rods connected at one end to the other said cross-head and mounted to swing about an axis extending transversely to the axis of the head to carry the other ends of said rods into and out of the grooves in the first said cross-head, slides in said grooves, and means for simultaneously moving said slides in opposite directions to cause them to engage or disengage the ends of the rods.

7. In a board holder for fabric winding machines, the combination of two aligned driving shafts, cross-heads secured to the 65 said shafts, a pair of parallel rods connected

at one end to one of the cross-heads and adapted to swing in parallel relation about an axis extending transversely of the axis of the head to carry the other ends of said rods into and out of engagement with notches 70 formed in the other cross-head, adjustable means for locking the rods in position in said notches, and an abutment extending between the rods and adjustable lengthwise of said rods for cooperating with the end of a 75 board supported thereon adjacent the relatively fixed ends of the rods, whereby the machine is adapted for use with winding boards of different lengths.

8. In a fabric winding machine, the combination of two aligned driving shafts, cross-heads secured to the said shafts, a pair of rods connected at one end to one of the cross-heads to swing about an axis extending transversely of the axis of the head to carry the other ends of said rods into and from notches 80 formed in and opening through the other cross-head, a winding board having tubular side members telescoping said rods, whereby the board may be positioned on or withdrawn from the rods when the latter are 85 swung out of engagement with said notches, adjustable means for locking the rods in position in said notches, and an abutment adjustable lengthwise of said rods for cooperating with the end of the board adjacent the relative fixed ends of the rods, whereby the machine is adapted for use with winding boards of different lengths.

9. A winding board for a fabric winding 100 machine comprising parallel tubular side members, transverse members connecting the side members, a covering extending over opposite faces of said members without obstructing the passages in the side members, and strips adapted to be secured to the ends of the board, said strips having projections adapted to enter the ends of the tubular side members.
